UNITED STATES PATENT OFFICE.

WILLIAM JOSEPH STILL, OF LONDON, ENGLAND.

INTERNAL-COMBUSTION ENGINE.

Application filed January 4, 1921. Serial No. 434,983.

To all whom it may concern:

Be it known that I, WILLIAM JOSEPH STILL, a subject of the King of Great Britain, and resident of London, England, have invented certain new and useful Improvements in and Relating to Internal-Combustion Engines, of which the following is a specification.

This invention relates to cylinders and pistons for internal combustion engines, and has for its object to provide a piston and cylinder construction which will permit of the employment of cylinders and pistons of greater area than as at present possible.

10 It is well known that the maximum diameter possible in practice for the cylinders and pistons of internal combustion engines is limited owing to the heat stresses. Except where special methods of cooling are provided for the piston, all the heat taken up by the piston as a result of combustion has to be transmitted to the cylinder walls and absorbed in the water of the cylinder jacket, and it will be readily seen that if 20 the rate of heat absorption is insufficient the piston soon becomes unduly hot, its centre being, of course, the hottest point.

For this reason in building engines of large power the method at present adopted 30 is to provide a multiplicity of cylinders each with its own accessories such as fuel valves, inlet and exhaust valves or ports, and it will be readily appreciated that this involves complications and practical difficulties when 35 it is remembered that the combustion chamber of the cylinders must each receive an equal quantity of air and fuel, and ignition must be equally perfect for all the cylinders if the engine is to perform efficiently.

40 In twelve cylinder sets as at present constructed considerable difficulty is experienced in timing the engines so as to obtain equal conditions in all cylinders at all loads, and if it were contemplated to provide say 42 cylinders the practical difficulties of obtaining equal distribution and efficient consumption would be such as to render such a proposition impossible of practical attainment.

50 It is the object of my invention to overcome these difficulties and the invention consists broadly in so disposing or dividing up the total piston area open to each combustion chamber that the parts of the area most remote from the influence of the cooling medium, are considerably nearer to said

cooling medium than would be possible with an ordinary piston giving the same effective area.

The invention further involves two particular practical embodiments one of which is the construction of the piston of annular form and the other of which consists in dividing the total piston area into a number of separate pistons all open to the same combustion chamber and all connected to a common cross-head. In the former of these arrangements cooling can be effected by jackets arranged both outside and inside the annulus and in the latter case the separate pistons can be completely surrounded by the cooling medium. It is thus possible to provide a much larger total piston area open to each combustion chamber than would be possible with a single piston of ordinary form.

In the accompanying drawings I have illustrated various embodiments of my invention diagrammatically,

Fig. 1 being a transverse sectional elevation of a double acting four cycle engine having an annular piston in accordance with my invention.

Fig. 2 is a sectional elevation of the cylinder and piston of a two cycle engine having an annular piston in accordance with my invention.

Fig. 3 is a view similar to Fig. 2 showing how concentric annular pistons can be provided.

Fig. 4 is a sectional elevation illustrating the alternative method of dividing up the piston area into separate elements all open to a single combustion chamber and all connected to a common cross-head and

Fig. 5 is a diagrammatic plan showing the disposition of the separate pistons which cumulatively form the total piston area.

Referring to these drawings and particularly to Fig. 1 the numeral 1 designates an annular piston which slides in the annular cylinder 2 and is maintained in gas tight engagement by means of packing rings 3 fitted in its inner periphery similar packing rings 4 fitted in its outer periphery and packing rings 5 fitted in the cylinder end 6. An external cooling jacket 7 is provided and there is also an internal space 8 for the circulation of the cooling medium. It is thus clear that the piston is subjected to the influence of the cooling medium from both sides and although the piston area can be

considerable there is no part of it which cannot be effectively cooled.

The operation of the engine will be well understood the combustible charges entering 5 the combustion chambers through the automatic inlet valves 9 while exhaust takes place through the cam operated valves 10. It will be seen that incidentally my invention overcomes the difficulty hitherto experienced 10 in double acting pistons of providing effective cooling for the piston rod.

Referring to Fig. 2 the annular piston 11 slides in the cylinder 12 and spaces or jackets 13, 14 and 15 are provided for the 15 circulation of the cooling medium which can thus act upon both walls of the annular piston which co-operates with the inlet ports 14¹ and exhaust ports 15¹ in the manner usual in two cycle engines.

20 Fig. 3 illustrates the possibility of providing annular pistons concentrically one within the other. These pistons 16 and 17 slide in the annular cylinders 18 and 19 and co-operate with the inlet and exhaust ports 20 and 25 21 respectively which of course are common to the two annular cylinders 18 and 19 which are open to a common combustion space 22. Here again each of the annular pistons is subjected to cooling from both 30 sides by means of the cooling medium circulated through the cooling jackets or spaces 23, 24 and 25. The numeral 26 designates the cylinder cover which is bolted by means of suitably disposed bolts 27 to the outer 35 wall of the cylinder structure and it will be understood that both the pistons are connected together by a common cross head 28 which is in turn coupled to the engine crank shaft in the usual way.

40 An alternative arrangement by which the desired effective cooling can be obtained is illustrated in Figs. 4 and 5. In this arrangement the total piston area is made up of a number of separate pistons 28 each operating 45 in its own cylinder 29 but all these cylinders are connected to one combustion chamber or space 30 and all the pistons are coupled to a common cross-head 31 and operate in unison. In this arrangement each 50 cylinder is surrounded by cooling jackets and thus although the cumulative piston area open to the combustion chamber is considerably more than has hitherto been possible in one cylinder effective cooling is provided 55 while the complications of separate cylinders with their separate valves and accessory devices is obviated.

The practical advantages of this form of my invention may be realized by assuming, 60 by way of example, that a cylinder of 16" diameter is satisfactory in practice but that a 26" diameter cylinder is not practical. The required power can be obtained according to my invention with a single combustion chamber by providing three cylinders

of 16" diameter each having its own piston but all opening to the one common combustion chamber with its single fuel valve, ignition plug and so forth. Taking a further example, if seven cylinders of 16" diameter were employed united to a common combustion chamber, they would—at the same speed and working pressure—give a power output corresponding to that of a cylinder of over 40" diameter, and the heat stresses 70 within the cylinders would vary but little from those obtaining in a single cylinder of 16" diameter. Seven cylinders could be arranged as indicated in Fig. 5 or in a group of six in a circle around a central 75 one but the combustion chamber in such cases would probably be subject to certain disadvantages, and for this reason I prefer, in most cases, to obtain the desired relation of surface to volume by the use of the 80 annular forms of cylinder and piston hereinbefore described.

In these annular pistons the radial width of the piston can be regulated according to the speed and working pressure of the engine so as to control the rate of heat flow within safe limits, slow speed engines, operating on low mean effective pressures, having pistons that are wider and have more surface for a given diameter than those 95 designed for higher speed and pressure. Both the foregoing arrangements are, however, in accordance with the same general principle.

What I claim and desire to secure by Letters Patent is:—

1. A large internal combustion engine comprising a cylinder having a central chamber, a jacketed outer wall, a circular screen in the form of an annulus disposed centrally and longitudinally within the jacketed outer wall and arranged to shield every part of the inner surface of the outer wall from some of the heat particles produced by combustion and contained within the cylinder and coating with said jacketed outer wall to form an annular chamber therebetween, said cylinder also having a chamber to contain a cooling medium arranged centrally in said cylinder and spaced 105 from the first named central chamber, means for supplying cooling fluid to the outer jacketed wall, the interior of the circular screen and the said second named central chamber, and an annular piston arranged 110 in sliding contact with both the outer wall of the cylinder and the central circular screen.

2. A large internal combustion engine comprising a cylinder having a central chamber, a jacketed outer wall, a circular screen in the form of an annulus disposed centrally and longitudinally within the jacketed outer wall and arranged to shield every part of the inner surface of the outer wall from 115 120 125 130

some of the heat particles produced by combustion and contained within the cylinder and coacting with said jacketed outer wall to form an annular chamber therebetween, 5 said annular chamber communicating with said central chamber, said cylinder also having a chamber to contain a cooling medium arranged centrally in said cylinder and spaced from the first named central chamber, means for supplying cooling fluid 10 to the outer jacketed wall, the interior of the circular screen and the said second named central chamber, and an annular piston arranged in sliding contact with both the outer wall of the cylinder and the central circular 15 screen.

In witness whereof I affix my signature.
WILLIAM JOSEPH STILL.
